UNITED STATES PATENT OFFICE.

JOHN L. HARRINGTON, OF WINSTON-SALEM, NORTH CAROLINA, ASSIGNOR TO SOUTHERN IMPLEMENT MANUFACTURING CO., OF COLUMBUS, GEORGIA, A CORPORATION OF GEORGIA.

THRESHING-MACHINE.

1,350,452.

Specification of Letters Patent. Patented Aug. 24, 1920.

Application filed November 3, 1919. Serial No. 335,256.

To all whom it may concern:

Be it known that I, JOHN L. HARRINGTON, a citizen of the United States, residing at Winston-Salem, in the county of Forsyth and State of North Carolina, have invented certain new and useful Improvements in Threshing-Machines, of which the following is a specification, reference being had to the accompanying drawings.

- 10 This invention relates to certain improvements in threshing machines, and is an improvement on the machine embodied in my prior Patent No. 1,035,437, dated August 13, 1912, and it is an object of the invention to provide a novel and improved machine of this general character which can be employed with equal facility in the picking or separating of peanuts and in threshing wheat or other grain.
- 20 Another object of the invention is to provide a novel and improved machine of this general character wherein the separated peanuts or grain are effectively freed of foreign matter, such as dirt, vines, straw and the like, and wherein the machine operates in a manner to substantially eliminate loss in the desired product.

An additional object of the invention is to provide a novel and improved machine of this general character wherein the peanut vines are first delivered to a coacting cylinder and concave, and wherein the working face of the concave is smooth and unobstructed, and which concave is mounted in working position in such a manner as to permit its ready replacement by a tooth concave, so that the machine may be readily employed in connection with wheat or other grain.

40 Furthermore it is an object of the invention to provide a novel and improved machine of this general character including an endless carrier for the vines or straw, and upon which the concave discharges, and wherein a vibratory screen or separating element is positioned below and in close proximity to the upper or receiving stretch of the carrier.

A still further object of the invention is 50 to provide a novel and improved machine of this general character embodying an endless carrier for the vines or straw, and with

which coacts a picking mechanism which operates to separate peanuts carried by the vines when traveling with the carrier, and which mechanism also operates to facilitate the separation of grain which may be carried by the straw.

The invention also has for an object to provide a novel and improved machine of this general character including a carrier and a picking mechanism coacting therewith, and wherein said picking mechanism includes means adjustable with respect to the carrier to impose pressure upon the vines or the like, moving with the carrier to facilitate the operation of the machine.

The invention has for a still further object the provision of a novel and improved machine of this general character embodying a separating element delivering upon members for conveying the separated peanuts or grain to a point substantially central of the screening element, and delivering the matter carried thereby to a riddle positioned therebeneath to effect a further means for separation, and wherein an air blast coacts with said riddle to carry off dust or other relatively minute particles of waste.

It is also an object of the invention to provide a novel and improved apparatus of this general character embodying means whereby the tailings, and particularly the tailings separated by the riddle are returned for further treatment by the machine so that the waste of the product separated, such as peanuts or grain, is substantially entirely eliminated.

The invention consists in the details of construction and in the combination and arrangement of the several parts of my improved threshing machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings:

Figure 1 is a view in side elevation with

a portion broken away, of a threshing machine constructed in accordance with an embodiment of my invention;

5 Fig. 2 is a longitudinal vertical sectional view taken through the machine, as illustrated in Fig. 1;

Fig. 3 is an enlarged fragmentary sectional view taken substantially on the line 3—3 of Fig. 2;

10 Fig. 4 is an enlarged view in perspective of one of the picking elements comprised in the picking mechanism;

Fig. 5 is an enlarged fragmentary view taken longitudinally through the picking mechanism, and the parts concomitant thereto;

Fig. 6 is a fragmentary sectional view taken substantially on the line 6—6 of Fig. 5;

20 Fig. 7 is an enlarged fragmentary view in cross section illustrating a mounting for the vibratory screening element or sieve, as herein included, and the parts adjacent thereto;

25 Fig. 8 is a sectional view taken through a supplemental riddle or sieve, which is employed when the machine is used in connection with wheat or other grain, and,

Fig. 9 is an elevational view detached, of 30 the member herein employed for maintaining the discharge nozzle of the fan casing in desired position, or adjustment with respect to the riddle.

As disclosed in the accompanying drawings, F denotes a portable frame constructed in accordance with the requirements of practice, and which is provided at one end with a feed trough 1, which delivers upon a concave C. The concave C is particularly illustrated in Fig. 2 of the accompanying drawing, and which figure illustrates the machine in assembly for use in connection with peanuts. It is to be particularly noted that the concave C is imperforate, and has its working face free and unobstructed. The concave C is adapted to be readily removed, so that the same may be replaced with a tooth concave of a conventional type when it is desired to employ the machine in connection with wheat or other grain. The concave C is supported, as indicated at 2, for swinging movement in a vertical direction toward or from the coacting tooth cylinder T, as the occasions of practice may require, and as disclosed in Fig. 2 the vertical swinging adjustment of the concave C is accomplished through the instrumentality of a cam 3, coacting with a shoulder 4, carried by the concave. As this particular means for adjusting the concave C forms no part of my present invention, it is believed that a detailed description and illustration is unnecessary.

The peanuts and the vines, as lifted from the ground, are thrown in a conven-

tional manner within the trough 1 and feed 65 therefrom to the concave C, and while passing over the concave C are acted upon in the well known manner by the cylinder T. The cylinder T, as is well known, serves to carry the peanuts and vines over the concave. The 70 concave C delivers upon an endless carrier E, and more particularly the upper stretch thereof. The upper stretch of the carrier E extends from a point in advance of the concave C to a point immediately adjacent the 75 rear end of the frame.

The carrier E comprises the side chains 3', passing around the sprocket wheels 4', fixed to the suitably positioned shafts 5, rotatably supported by and extending transversely of the frame F. Each of the chains 3' coact with the idle guide wheels or pulleys 6, whereby said chains are prevented from sagging. One of the shafts 5 has each end portion engaged with an adjustable bearing 85 7, whereby the chains 3' may be held under proper tension. The opposite shaft 5 extends to a side of the frame F and said extended portion has affixed thereto a sprocket wheel 8, having in driving connection therewith the chain 9.

Fig. 9 is an elevational view detached, of 30 the member herein employed for maintaining the discharge nozzle of the fan casing in desired position, or adjustment with respect to the riddle.

The chains 3' are connected by the equidistantly spaced transverse members 10, each provided with a series of upstanding fingers 11 of desired length. 95

The vines or the like, as delivered upon the carrier E are carried rearwardly of the frame F and the separated peanuts pass through the vibratory screening element or sieve S positioned to and in close proximity 100 to the upper stretch of a carrier E. The screening element or sieve S is of a length to substantially bridge the space between the shafts 5, and is of a width substantially equal to the space between the side chains 3'. 105

The screening element or sieve S comprises the elongated side members 12, having secured to the upper edges thereof, in any desired manner, the reticulated fabric or screening 14, the openings of which being of 110 a size to readily permit the passage therethrough of the separated peanuts.

At predetermined points longitudinally thereof the side members 12 are connected by the cross members 15, which have their 115 opposite extremities disposed through the longitudinally directed slots 16, formed in the side walls of the frame F, whereby the element or sieve S is supported in applied position and capable of endwise vibratory 120 movement or reciprocation.

Each end portion of a cross member 15, and preferably the central member has engaged therewith the upper end portion of a vertically disposed hanger 17 pivotally supported intermediate its length, as at 18, by the adjacent portion of the frame F. Upon rocking or swinging movement being im-

parted to the hangers 17, the desired vibration or reciprocation of the element or sieve S is effected to facilitate the desired functioning of such element or sieve S.

5 The separated peanuts, together with foreign matter passing through the element or sieve S, drop upon the upper stretches of the longitudinally alined endless aprons or drapers 19. The adjacent portions of the 10 aprons or drapers 19 are spaced apart, as at 20, to afford a discharge passage and the upper stretches of the aprons or drapers 19 move in a direction toward such passage or opening, so that the material carried by the 15 aprons or drapers will be discharged through said passage or opening 20.

Each of the drapers 19 passes around the drums 21, carried by the suitably positioned shafts 22, rotatively supported by the frame 20 F. Each end portion of the outer shaft 22 is mounted in an adjacent bearing 23, whereby said apron or draper may be maintained under desired tension.

Adjacent shanks 22 extend beyond the 25 side of the frame F, and have affixed thereto the sprocket wheels 24, with which is operatively engaged a driving chain 25 in driven connection with the drive shaft 26, suitably supported by the frame F. The chain 9, 30 hereinbefore referred to, is also in driven connection with the shaft 26, as illustrated in Fig. 1 of the accompanying drawings. It is to be noted that the chain 25 coacts with the sprockets 24 in a manner to cause the 35 upper stretches of the aprons or drapers 19 to travel in a direction one toward the other, or in a direction toward the passage or opening 20, hereinbefore referred to.

The hangers 17, together with the hangers 40 17^a, have their lower extremities operatively engaged with the side plates 27, supporting a riddle 28. The openings of the riddle 28 are of a size to permit the passage therethrough of the separated peanuts. The 45 hangers 17 and 17^a support the riddle 28 for vibratory movement, and said riddle 28 is positioned below the opening or passage 20 to receive the matter discharged therethrough.

50 The riddle 28 is inclined rearwardly and downwardly, so that the tailings retained thereby will be discharged within the transversely disposed chute 29, delivering in the lower end portion of the housing or casing 55 30 for an elevating mechanism.

The upper end portion of the housing or casing 30 discharges within the trough 1, so that the tailings can be caused to be again treated by the machine, whereby the loss 60 of peanuts or the like is substantially eliminated. The elevating mechanism within the casing or housing 30 is of a conventional type, and for which reason a detailed description and illustration is believed to

be unnecessary other than to say that such 65 mechanism is in driven connection through the medium of the chain 31, with a sprocket 32, fixed to one of the inner shafts 22.

The peanuts passing through the riddle 28 are received on a forwardly and downwardly inclined table 33, suitably supported by the frame structure, and underlying said riddle. The table 33 is provided with a series of transversely spaced slots 34, through which extend from below the revolving saws 35.

70 As is particularly illustrated in Fig. 2, two longitudinally alined saws 35 extend through a slot 34, and for which reason said saws are arranged in two transversely disposed series. The saws 35 of each series are suitably affixed to a transversely disposed shaft 36, suitably supported for rotation by the frame F, and in a manner whereby said shaft 36 and the saws carried 75 thereby may be readily removed from working position.

80 The adjacent ends of the shafts 36 are operatively connected, as indicated at 37, for unitary rotation, and one of said shafts 90 36 is in driven connection with a shaft 22 by a chain 38, indicated by dotted lines in Fig. 2.

85 The saws 35 engage the peanuts delivered upon the table 33, and operate to stem said 95 nuts, and otherwise clean the same. The cleaned nuts are discharged from the table 33 into the delivery spout or trough 39 extending transversely of the frame on a predetermined downward incline, and delivering 100 at one side thereof.

95 The desired vibration or oscillation of the riddle 28 is obtained through the medium of the pitman 40, operatively engaged at one 105 end portion, with the lower extremity of the hanger 17, and the opposite end portion of the pitman 40 is operatively engaged with a shaft 41, suitably supported by the frame F. The shaft 41 has affixed thereto a pulley 42, around which passes a driving belt 43. 110 The belt 43 is also disposed around a pulley 44, fixed to the shaft 26, whereby said shaft 26 is properly driven. The belt 43 is adapted to be engaged with a suitable source of 115 power, and preferably with the driving pulley of a tractor, although I do not wish to be understood as limiting myself in this respect, as it is to be understood that the shafts 41 and 26 may be rotated in any manner which best meets the requirements 120 of practice. Overlying the rear end portion of the upper stretch of the endless carrier E and extending along the major length thereof, is a picker frame P, including the longitudinally spaced cross bars 45. Depending from the bars 45 are the picker teeth 46, of a type substantially the same 125 as disclosed in my prior Patent No.

1,035,437, hereinbefore referred to. The teeth 46 are yieldable and passing between adjacent teeth 46 are the upstanding fingers 11, hereinbefore referred to, and which is particularly illustrated in Fig. 6 of the accompanying drawings. As the upper stretch of the carrier E travels rearwardly and under the teeth 46, said teeth operate to pull or pick the peanuts from the vines or halm, and substantially all of the peanuts thus picked from the vines drop upon and through the element or sieve S.

The halm is discharged by the carrier E at the rear end of the frame F or machine, and falls clear thereof.

In order to prevent the vines or halm passing under the teeth 46 from becoming clogged within said teeth, and thereby interfering with the requisite operation of the machine, I find it of extreme importance to provide means for maintaining a downward pressure upon the vines or halm.

As herein disclosed I arrange below the picking frame P a plurality of transversely spaced and connected pressure bars 47, each of said bars extending between longitudinally aligned adjacent teeth 46. The bars 47 are adjustably engaged with the frame P, or more particularly the cross bars 45, thereof, by the upstanding threaded shanks 48, extending through certain of said cross bars. Engaged with each of the shanks 48 above and below the coating bar 45 are the clamping or holding members or nuts 49, whereby the bars 47 may be maintained in desired position with respect to the upper stretch of the carrier E. The frame P, hereinbefore referred to, is mounted in working position in substantially the same manner as disclosed in my prior patent, hereinbefore referred to, and for which reason a detailed description of such mounting is not believed necessary.

50 denotes a fan casing loosely mounted upon the transversely disposed shaft 51, rotatably supported by the frame F, and said casing 50 is provided with a discharge spout or nozzle 52 for delivering an air blast or current rearwardly of the frame, and which blast or current operates in the well known manner to carry off dust or other light particles of waste or trash, which is received upon or passes through the riddle 28.

55 The shaft 51 has fixed thereto and within the casing 50, the fan blades 53 of a conventional type, and said shaft 53 is in driven connection through the medium of the belt 54, with a pulley 55, fixed to one of the shafts 22.

60 By having the casing 50 loosely mounted upon the shaft 51 the nozzle or spout 52 may be readily raised or lowered to direct the air blast or current, as best meets the require-

ments of practice. The casing 50, or more particularly the spout or nozzle 52 thereof, is maintained in desired position by a cross beam or member 56, having its opposite end portions suitably engaged with the frame F, and preferably through the instrumentality of a bolt 57 passing through a transversely directed slot 58, in each end portion of the member 56. The slot 58 permits the member 56 to be vertically adjusted in accordance with the adjustment of the nozzle or spout 52. The opposite end portion of the member 56 is preferably provided with the hand grasp 59 to facilitate the manipulation thereof.

When the machine is to be employed to thresh wheat or other grain, the concave C is replaced by a tooth concave of the well known type, and engaged within a guideway 60, carried by each of the walls 27 at a point below the riddle 28 is the screening element 61, the openings of which being smaller than the openings in the riddle 28, but of a size to permit passage of the grain therethrough. The shafts 36 and saws 38 are also removed, and an imperforate plate, (not shown), is superimposed upon the table 33 and upon which the grain is dropped. This plate discharges the separated grain within the chute 39. Otherwise the operation of the machine in the threshing of wheat or other grain is similar to what has hereinbefore been set forth with respect to the use of the machine in connection with peanuts.

The belt 43 also engages a pulley 62 fixed to an extended end portion of the shaft 63 for the cylinder T, whereby said cylinder is properly rotated. If preferred, however, other means may be employed for operating the cylinder.

From the foregoing description it is thought to be obvious that a threshing machine constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

1. A machine of the class described including a separating element, a carrier movable above said element, picker teeth supported above the carrier, and a compression member disposed between adjacent teeth.

2. A machine of the class described including a separating element, a carrier movable above said element, picker teeth sup-

ported above the carrier, and a compression member disposed between adjacent teeth, said compression member extending in the same general direction as the direction of travel of the carrier.

3. A machine of the class described including a separating element, a carrier movable above said element, picker teeth sup-

ported above the carrier, and a compression member disposed between adjacent teeth, 10 said member being adjustable in a vertical direction.

In testimony whereof I hereunto affix my signature.

JOHN L. HARRINGTON.
